JOSEPH HAINES, JR., OF MEADOWBROOK, PENNSYLVANIA, ASSIGNOR TO HAINES HOSIERY MILLS, INC., OF PHILADELPHIA, PENNSYLVANIA, A CORPORATION OF PENNSYLVANIA

WELT CLOSING MECHANISM FOR FULL FASHIONED KNITTING MACHINES

Application filed February 24, 1930. Serial No. 430,566.

This invention relates to full fashioned hosiery knitting machines, and has more especial reference to mechanism useful in connection with such machines to close the 5 welts at the tops of stocking blanks.

As is well known to those conversant with this art, turning and closing of welts by hand on full fashioned hosiery knitting machines is a very tedious operation which necessitates the exercise of great skill and therefore employment of high salaried help. Notwithstanding, the operation is often attended by dropping of the fabric loops incident to transfer from the loop engaging instrumentalities of the welt bars back to the knitting needles, and in the formation of "seconds" which must be disposed of at a loss. Another disadvantage is that it entails stoppage of the machines for protracted periods with corresponding curtailment in production.

The chief aim of my invention is to overcome the above recited drawbacks with a view toward increasing the output of the machines and correspondingly minimizing manufacturing costs, through provision of a simple means in the form of an attachment capable of being readily adapted to standard machines, and of effecting closure of stocking welts automatically.

A further aim of my invention is to enable employment of the narrowing mechanism of the machines to perform all manipulations of the welt bars essential to the welt closing operation.

Still further objects and attendant advantages of this invention will be manifest from the detailed description following when considered in connection with the accompanying drawings; whereof Fig. I is a cross sectional view of a typical full fashioned hosiery knitting machine conveniently embodying my improved welt closing mechanism.

Fig. II is a fragmentary elevation of the front of the organization, or as viewed from the right of Fig. I, comprehending one of the double needle bar sections of the machine.

Fig. III is a detail view in front elevation, on a somewhat larger scale than the preceding illustrations, showing the means whereby the welt bars are removably attached

to the narrowing mechanism of the machine for actuation by said mechanism to automatically close stocking welts.

Fig. IV is a detail cross sectional view, on a still larger scale, taken as indicated by the arrows IV—IV in Fig. III. 55

Fig. V is a fragmentary detail cross sectional view of the machine showing the knitting instrumentalities in the position which they ordinarily occupy while forming the fabric for a stocking welt, and featuring certain of the parts associated with the present invention. 60

Figs. VI and VII are detail views showing the cooperation of the needles and sinkers of the machine with the loop engaging instrumentalities of the welt bars during the welt closing operation in accordance with my invention. 65

Fig. VIII is a fragmentary cross sectional view of the machine, similar to Fig. I, showing more particularly the means provided for modifying the normal action of the narrowing mechanism of the machine for the purposes of automatic welt closure. 70

Fig. IX is a perspective view showing how the welt bars for each knitting section of the machine are mounted in aligned relation to a holder bar in pairs to facilitate their application to the narrowing mechanism; and, 75

Fig. X is a perspective view of a special type of loop engaging instrumentality for the welt bars which I prefer to employ in connection with my welt closing mechanism.

Referring first more especially to Figs. I and II of these illustrations, the numeral 12 designates a needle bar whereof there is one associated with each knitting section of the machine as usual, said bar carrying, in aligned relation, two sets of needles 13 for knitting as many separate stocking blanks at a time. The needle bar 12 is moved up and down in the interval between the transverse frames 14, 14a of the machine relative to the horizontally cooperating sliding sinkers 15 and the rocking knock-over bits 16, by means of arms 17 on a horizontal rock shaft 18, said rock shaft being oscillated through suitable connections (not shown) with the longitudinally extending cam shaft 19 of the machine. 85 90 95 100

The catch bar 20 for the sinkers 15 is likewise actuated by a cam (not illustrated) on the shaft 19, through a roller arm partly shown at 21 in Fig. I, which roller arm is secured to a horizontal rock shaft 22 at the back of the machine. Another arm 23 on the rock shaft 22 is directly connected, by means of a link 24, with the catch bar 20. The narrowing mechanism of the machine, comprehensively designated 25, has the usual curved arms 26 which reach upward and forwardly from another rock shaft 27 at the back of the upper portion of the machine, and support a rod 28 between them directly over the knitting instrumentalities 13, 15 and 16. Shiftable endwise in pendant brackets 29 on the rod 28 are the horizontal slide bars 30, 31 whereto are respectively secured the narrowing combs 32, 33 which are instrumental in shaping the stocking blanks after a well known manner. Dipping motion is imparted to the arms 26 and their appendages through a downward link 34 having pivotal connection at its upper end with the rod 28 and at its lower end, with a lever 35. This lever 35 is rockable about a stud 36 on the transverse frame 14, and, as shown, carries, intermediate its ends, a roller 37, which, during ordinary narrowing, is adapted to be influenced by the narrowing cam 38 on the cam shaft 19. The means whereby the narrowing mechanism 25 may be lifted manually for retention in idle position when required, includes a crank handle 39 which is fulcrumed at 39a on the frame 14a and coordinated, by means of a rod 40, with a lever 41 on still another rock shaft 42 that extends longitudinally of the lower rear part of the machine, see Figs. I, II and VIII. On this shaft 42 is secured a stop arm 43 with a roller 43a, which, when the crank handle 39 is moved outward from the position shown in Fig. I, is swung beneath the free end of the lever 35, thereby to hold the narrowing mechanism 25 raised as aforesaid with the roller 37 on said lever clear of the narrowing cam 38.

In carrying out my invention, I permanently secure the two welt bars 45 associated with each knitting section of the machine in aligned relation to a holder bar 46, see Figs. V and IX. As shown, the holder bar 46 is of angular cross section, and provided in that flange 46a thereof whereto the welt bars 45 are directly secured, with gage holes 47, and in the complementary lateral flange 46b at corresponding points with quadrangular apertures 48 for a purpose later on explained. During knitting of the stocking welts, the holder bar 46 is sustained by slideways 49 (Figs. I and V) fixed crosswise of the top longitudinal channel rail 50 at the front of the machine frame. At the rear, the holder bar 46 is equipped at suitable intervals, with apertured lugs 51 to receive the hooks of the draw straps 52 on the take-up roll indicated at 53 in Fig. I, said take-up roll extending between brackets 54 that reach horizontally outward from the channel rail 50 in the planes of the transverse frames 14, 14a of the machine. The loop engaging instrumentalities 55 which I employ in the welt bars 45, it will be noted from Figs. VI, VII and X, are of the latch hook variety, their latches 56 having considerable extent beyond the hook ends to facilitate their ready opening simultaneously in preparation for engaging the loops L (Figs. VI and VII) of the first course of the welt fabric F in starting new stocking blanks. For this operation, a latch opening means comprehensively designated 57 in Fig. I is provided. This latch opening means 57 is fully disclosed in a separate patent application, Serial No. 421,547 filed by Harold F. Paget on January 17, 1930, and need not therefore be described in detail herein. A further feature to be noted in connection with the loop engaging instrumentalities 55 of the welt bars 45 is that the backs of their shanks are grooved or fluted as at 57 to receive the beards 13a of the needles 13 incident to loop transfer in welt closing after the manner shown in Figs. VI and VII, and as described in greater detail later on. After a predetermined length of fabric F has been knit for the welts of the stockings, the holder bar 46 with its welt bars 45 is applied to the narrowing mechanism 25 as shown in Figs. I, II and III, that is to say, the tapered flange 46b of said bar is inserted in the interval between the two narrowing comb bars 30, 31 and its gage holes 47 registered with corresponding allocated gage studs or pins 60, (Figs. III and IV) on the narrowing comb bar 31. To lock the holder bar 46 against displacement when so applied, I provide at the rear of the narrowing comb bars 30, 31, a pair of latches 61 to engage the apertures 48 in the flange 46b of said holder bar, see Figs. II, III and IV. As shown, these latches 61 are vertically slidable in guide pieces 62 secured to the rod 28 of the narrowing mechanism 25, and are coordinated for simultaneous operation by a horizontal cross beam or connector 63, which, at its center, has a longitudinal slot 64 adapted to be engaged by the crank pin 65 of a manipulating handle 66. A yoked bracket 67 secured to the rod 28, see Figs. II and III, affords the axis 68 of the manipulating handle 66 fulcrum support; and means in the form of a spring pressed ball 69 to engage with circumferential notches 70, 71 in the boss of the yoke bracket 67 is relied upon to hold the manipulating handle 66 yieldingly, either in the "on" position of Fig. II, or the "off" position of Fig. III.

Incident to ordinary narrowing, the mechanism 25 is caused to dip twice, first to take the loops L from the needles 13, and again after shifting of the transfer comb bars 30, 31 to place such loops on adjacent needles. In order to modify the action of the narrow-

ing mechanism 25 for the purposes of my invention I provide means for eliminating one of the two dips above referred to. This means includes as shown in Figs. I, II and 5 VIII, an arm 72, which, for convenience, is shown as being mounted for free swinging movement on the loop regulating shaft 73 at the front of the machine, said arm having its end rounded as at 72a to engage a collar 74 on the rod 40 that extends between the handle 39 and the lever 41 associated with the roller arm 43 on the rock shaft 42. In order 10 that the stop or roller arm 43 may be actuated independently of the handle 39, the rod 40 is slidingly engaged in a swivel stud 75 in a lug 39b of said handle. Beyond the swivel stud 75 the rod 40 is fitted with a second collar 76 to cooperate with said swivel incident to manual actuation of the roller arm 15 20 25 30 35 40 45 50 55 60 65 70 75 80 85 90 95 100 105 110 115 120 125 130

43 by the handle 39. From the arm 72 projects laterally a stud 77 whereon is slidingly mounted a roller 78 which is shiftable by means of a hand lever 79 into the plane of a supplemental rotary cam 80 on the cam shaft 19 of the machine. From Fig. VIII it will be noted that when the roller 78 rides the high portion 80a of the supplemental cam 80, the roller arm 43 is pulled forward into active position to intercept the lever 35 and to hold the narrowing mechanism 25 raised while the low portion 38a of the narrowing cam 38 passes beneath the roller 37 on the lever 35, thereby preventing the usual first dip of said narrowing mechanism. When however, the high portion 80a of the supplemental cam 80 passes beyond the range of the roller 78 on the arm 72, the lever 35 is released in time to be actuated by the second low portion 38b of the narrowing cam 38 so that the narrowing mechanism 25 is permitted to perform the one dip necessary to welt closure in the manner presently explained.

The method of welt turning and closing with the mechanism of my invention is as follows: Assuming that the proper length of fabric F (Figs. V, VI and VII) has been knit on each set of the needles 13, and that the machine has been automatically stopped in the usual way by the means provided for that purpose in readiness for welt turning, the straps 52 of the take-up roller 53 are unhooked from the holder bar 46. The holder bar 46 is then lifted from off its guides 49 (Figs. I and V) and mounted on the narrowing mechanism 25. Incident to this step, the tapered flange 46b of the holder bar 46 is inserted in the interval between the two vertically-spaced narrowing comb bars 30, 31 of the mechanism 25 as hereinbefore explained, care being taken to register the holes 47 in the flange 46a with the studs 60 on the comb bar 31, whereupon the manipulating handle 66 is swung from the position of Fig. III to the position of Fig. II to thrust the latches 61 down into the apertures 48 of the flange 46b, of said holder bar, thereby locking the latter firmly in position. The hand lever 79 is next thrown to the left in Fig. II to shift the roller 78 into the plane of the supplemental rotary cam 80 on the main cam shaft 19. All being now in readiness, the machine is started and the cam shaft 19 automatically shifted toward the right precisely as if a narrowing operation were to be performed, the narrowing cam 38 being thus positioned to influence the lever 35. At the inception of the ensuing rotation of the cam shaft 19, it is to be understood that, under the influence of the supplemental cam 80, the roller arm 43 is caused to intercept the lever 35, thereby to prevent the first dip of the narrowing mechanism 25, also as previously explained. However, when the high portion 80a of the supplemental cam 80 has cleared the roller 78, the roller arm 43 is moved from beneath the lever 35 permitting the roller 37 to contact with the narrowing cam 38 during the final half revolution of the latter, to the end that the mechanism 25 with the welt bars 45 is moved downward. The hook instrumentalities 55 of the welt bars 45 are thereby lowered to the position shown in Fig. VI to meet the needles 13 and to sheath the beards 13a of said needles within the flutings 57 of their shanks. Such contact as between the needles 13 and the instrumentalities 55 is brought about while the sinkers 15 are retracted as in Fig. VI so that the loops L of the initial course of the fabric on said instrumentalities are impaled upon the needles 13 in a manner simulative of loop transfer incident to ordinary narrowing. Then with the needles 13 and the instrumentalities 55 still in the position of Fig. VI, the sinkers 15 are advanced, through movement of the catch bar 20 (as during an ordinary narrowing cycle), into position over the loops L as in Fig. VII, whereupon as the narrowing mechanism 25 is lifted in completing its dip, the hook instrumentalities 55 of the welt bars 45 are withdrawn from said loops L, the latches 56 of said instrumentalities closing automatically after the manner of ordinary latched knitting needles. The loops L are thus retained by the needles 13 and the welt closed over the course of loops L last knit. After having passed through a single narrowing cycle as just explained, the machine is caused to resume its normal mode of operation automatically to continue knitting the leg portions of the stockings. The instrumentalities 55 being now free of the fabric F, the holder bars 46 are removed from the narrowing mechanism 25 upon release of the latches 61 by a return swing of the manipulating handle 66 in readiness to be used for the next set of stocking blanks. The hand lever 79 is at the same time shifted to its normal position so that the roller 78 is kept out of the way of the supplemental

cam 80 during the narrowing periods which follow the welt closing operation incident to completion of the stocking blanks on the machine.

5 From the foregoing it will be seen that I have provided a very simple means by which the operation of welt closing is performed automatically, said mechanism being in the form of an attachment readily adaptable to 10 standard knitting machines. The time interval required to carry out the only hand operation involved, namely, that of placing the welt bars 45 on the narrowing mechanism 25 is greatly shortened through mounting of the two welt bars 45 of each section on a common holder bar 46 to the end that even from this standpoint the production on the machines is perceptibly speeded.

Having thus described my invention, I 20 claim:

1. The combination in a full fashioned knitting machine embodying a series of needles, narrowing mechanism, and means for imparting dipping motion to the narrowing mechanism; of welt closing mechanism including a welt bar fitted with loop engaging instrumentalities and adapted to be removably attached to the narrowing mechanism for utilization of the dipping motion of 25 the latter to effect transfer of the initial course of fabric loops on the welt bar instrumentalities back to the needles of the machine, gage means for determining the position of the welt bar on the narrowing mechanism to pre- 30 assure accurate registry of the loop engaging instrumentalities with the needles, and latch means for securing the welt bar against displacement on the narrowing mechanism.

2. The combination in a full fashioned 40 knitting machine embodying a series of needles, narrowing mechanism, and means for imparting dipping motion to the narrowing mechanism; of welt closing mechanism including a welt bar fitted with loop engaging 45 instrumentalities and adapted to be removably attached to the narrowing mechanism for utilization of the dipping motion of the latter to effect transfer of the initial course of the fabric loops on the welt bar instrumentalities back to the needles of the knitting machine, and means securing the welt bar against displacement on the narrowing mechanism comprising a number of latches for engaging 50 said bar at intervals, and means for simultaneously actuating said latches.

3. The combination in a full fashioned 55 knitting machine embodying a series of needles, narrowing mechanism, and means for imparting dipping motion to the narrowing mechanism; of welt closing mechanism including a welt bar fitted with loop engaging 60 instrumentalities and adapted to be temporarily attached to the narrowing mechanism for utilization of the dipping motion of the latter to effect transfer of the initial course

of the fabric loops on the welt bar instrumentalities back to the needles of the machine, a 70 number of sliding latches for engaging the welt bar at intervals to secure it against displacement on the narrowing mechanism, a common connector for the latches, and an actuating handle with an eccentric pin to engage a longitudinal slot in said connector.

4. The combination in a full fashioned 75 knitting machine embodying a series of needles, narrowing mechanism with vertically spaced longitudinal slide bars carrying narrowing combs; of welt closing mechanism including a welt bar fitted with loop engaging instrumentalities and adapted to be removably attached to the narrowing mechanism for 80 utilization of the dipping motion of the latter to effect transfer of the initial course of the fabric loops on the welt bar instrumentalities back to the needles of the machine, said welt 85 bar having a perpendicularly projecting lateral flange capable of engaging in the interval between the two slide bars aforementioned of the narrowing mechanism, and latch means to secure the welt bar against 90 displacement on the narrowing mechanism.

5. The combination in a full fashioned 95 knitting machine embodying a series of needles, narrowing mechanism with vertically spaced longitudinal slides carrying narrowing combs; of welt closing mechanism including a welt bar fitted with loop engaging instrumentalities and adapted to be removably attached to the narrowing mechanism for 100 utilization of the dipping motion of the latter to effect transfer of the initial course of the fabric loops on the welt bar instrumentalities back to the needles of the machine, said welt bar having a perpendicularly projecting lateral flange capable of engaging in the interval between the two slide bars aforementioned of the narrowing mechanism, a number of latches disposed behind the slide bars to engage apertures arranged at intervals 105 along the flange of the welt bar to hold said bar against displacement on the narrowing mechanism, and means to actuate the latches.

6. The combination in a full fashioned 110 knitting machine embodying a number of 115 knitting sections each with a plurality of sets of needles in longitudinal alignment, a narrowing mechanism individual to each section and means for imparting dipping motion to such narrowing mechanism; of welt closing 120 mechanism including holder members with permanently attached welt bars corresponding to the number of needle banks in each machine section, said welt bars being arranged in aligned relation on the holder members and each fitted with loop engaging instrumentalities, and latching means whereby said holder members are detachably secured to the narrowing mechanism for utilization of the dipping motion of the latter to effect transfer of 125 the initial courses of the several fabric sec- 130

- tions on the welt bar instrumentalities back to the needles of the machine incident to automatic welt closing.
7. The combination in a full fashioned knitting machine embodying a series of needles, narrowing mechanism, and cam actuated means determining a double dip of said narrowing mechanism during the ordinary narrowing phases of the knitting; of welt closing mechanism including a welt bar fitted with loop engaging instrumentalities and adapted to be removably attached to the narrowing mechanism; means whereby, for the purposes of automatic welt closure, the action of the narrowing mechanism is modified with impartation of but a single dip to the welt bar in effecting transfer of the initial course 20 of fabric loops on the welt bar instrumentalities back to the needles of the machine.
8. The combination in a full fashioned knitting machine embodying a series of needles, narrowing mechanism, and a rotary cam with low points to determine a double dip of the narrowing mechanism during the ordinary narrowing phases of the knitting; of welt closing mechanism including a welt bar fitted with loop engaging instrumentalities and adapted to be removably attached to the narrowing mechanism, and means whereby, for the purposes of automatic welt closure, the effect of one of the low points of the rotary cam aforesaid is nullified with impartation of but a single dip to the welt bar and with incidental transfer of the initial course of fabric loops on the welt bar instrumentalities back to the needles of the machine.
9. The combination in a full fashioned knitting machine embodying a series of needles, narrowing mechanism, and a rotary cam with low points determining, by cooperation with a lever, a double dip of said narrowing mechanism during the ordinary narrowing phases of the knitting; of welt closing mechanism including a welt bar fitted with loop engaging instrumentalities and adapted to be removably attached to the narrowing mechanism, and means whereby, for the purposes of automatic welt closure, the lever aforesaid is temporarily withheld from the influence of the cam with impartation of but a single dip to the narrowing mechanism and the attached welt bar to effect transfer of the initial course of the fabric loops on the welt bar instrumentalities back to the needles of the machine.
10. The combination in a full fashioned knitting machine, embodying a series of needles, narrowing mechanism, a rotary cam with low points to determine, by cooperation with a lever, a double dip of said narrowing mechanism during the ordinary narrowing phases of the knitting, and a manually opera-
- ble stop arm capable of intercepting the lever and withholding it from the influence of the cam; of welt closing mechanism including a welt bar fitted with loop engaging instrumentalities and adapted to be removably attached to the narrowing mechanism; means whereby, for the purposes of automatic welt closure, the stop arm aforementioned is automatically operated independently of its manual actuation, means to temporarily restrain the lever from the influence of the cam with impartation of but a single dip to the narrowing mechanism and the attached welt bar to effect transfer of the initial course of the fabric loops on the welt bar instrumentalities back to the needles of the machine.
11. The combination in a full fashioned knitting machine embodying a series of needles, narrowing mechanism, a rotary cam with low points to determine, through cooperation with a lever, a double dip of said narrowing mechanism during the ordinary narrowing phases of the knitting, and a stop arm capable of being moved into the path of said lever to intercept its movement and to withhold it from the cam; of welt closing mechanism including a welt bar fitted with loop engaging instrumentalities and adapted to be removably attached to the narrowing mechanism, a supplemental cam operative to automatically move the stop arm temporarily into position to intercept the lever and thereby predetermine, for the purposes of automatic welt closure, but a single dip of the narrowing mechanism and the attached welt bar to effect transfer of the initial course of fabric loops on the welt bar instrumentalities back to the needles of the machine.
- In testimony whereof, I have hereunto signed my name at Philadelphia, Pennsylvania, this 20th day of February, 1930.
- JOSEPH HAINES, JR.
